UNITED STATES PATENT OFFICE.

GEORGE C. SWEET, OF THE UNITED STATES NAVY.

AUTOMATIC BRAKE-CONTROLLING DEVICE.

1,084,503.

Specification of Letters Patent. Patented Jan. 13, 1914.

Application filed November 18, 1912. Serial No. 782,089.

To all whom it may concern:

Be it known that I, GEORGE C. SWEET, lieutenant commander, United States Navy, a citizen of the United States, recently attached to U. S. S. *Iowa*, have invented certain new and useful Improvements in Automatic Brake-Controlling Devices; and I do hereby declare the following to be a full, clear, and exact description of the invention, such as will enable others skilled in the art to which it appertains to make and use the same.

My invention relates to improvements in automatic brake-controlling devices, and it consists in the constructions, combinations and arrangements herein described and claimed.

An object of my invention is to provide an improved construction adapted to act with certainty under all conditions to prevent the unintentional entrance of a train on an occupied block section.

A further object of my invention is to provide an improved construction which will insure an automatic control of the air brakes entirely independently of manual operations, and which will give immediate warning of any inoperativeness or derangement of its parts.

In the accompanying drawings forming a part of this application, and in which similar reference symbols indicate corresponding parts in the several views:—Figure 1 is a diagrammatical view, illustrating one embodiment of my invention applied to a brake train-pipe, portions of the locomotive and tender being indicated by broken lines; Fig. 2 is an enlarged, detail sectional view of the construction shown in Fig. 1, and the various air connections thereof; Fig. 3 is a detail view, illustrating a slight modification of the electro-magnetic device shown in Fig. 2; Fig. 4 is a detail side elevation illustrating a modified construction; Fig. 5 is a vertical section, showing a preferred construction and its relation to the track and magnetic rails; Fig. 6 is a detail end elevation of the rails and co-operating roller shown in Fig. 5; Fig. 7 is a diagrammatical view, illustrating my improved connections to the block sections of a track; Fig. 8 is a similar view, illustrating a modified form of connections; and Fig. 9 is a similar view, illustrating a further modification.

Referring especially to Figs. 1-3 of the drawings, 1 indicates a valve for releasing

the air pressure in a train-pipe 2 for throwing on the brakes; said valve being actuatingly connected by a link 3 to a piston valve, or plunger, 4 shiftably mounted in a casing 5 provided with an exhaust opening 5^a. The plunger 4 is connected by a link 6 to a lever 7 fulcrumed at 8 and carrying a shoe 9 adapted to ride on a magnetic cam-rail 10 supported adjacent to the track 11 near the end of a block section.

An engineer's valve 12 is mounted in a casing 13, provided with exhaust openings 14 and 15 and connected by independent pipes 16, 17 and 18 with said casing 5; a suitable source of air under pressure, such as a reservoir 19, being connected by branch pipes 20 and 21 with said casings 5 and 13, respectively.

In the normal position of the engineer's valve 12 shown in Fig. 2, air under pressure is admitted through the pipe 21, casing 13 and pipe 17 to the casing 5 beneath a piston head 22 on the plunger 4, thereby normally maintaining said plunger in raised position; the pipe 20 being closed by the plunger 4, and the pipes 16 and 18 maintained in communication with the exhaust openings 15 and 5^a, respectively. If the shoe 9 be now elevated by the cam-rail 10, the plunger 4 will be depressed to cut-off the pipe 18 from the exhaust 5^a, and to place said pipe in communication with the air-pressure pipe 20, thereby admitting air through said pipe 18 to the casing 13 beneath the valve 12 for forcing the latter to its upper position. This upward shifting of the valve 12 closes the exhaust opening 15, places the pipe 17 in communication with the exhaust opening 14, and places the pipe 16 in communication with the air-pressure pipe 21 for admitting air through said pipe 16 above the piston head 22 in the casing 5; thereby forcing the plunger 4 downward and maintaining it in its lower position. This downward shifting of the plunger 4 acts through the link 3 to open the valve 1 for applying the emergency operation of the brakes.

If the magnets 23 of the cam-rail 10 be energized during such travel of the shoe 9 thereon, electrical currents will be induced in coils 24, carried by said shoe in electrical connection with the winding of an electro-magnet 25, or with a relay which closes a local circuit, in the engine cab, through the windings of magnet 25, such as shown in

Fig. 5. The magnet 25 will thus be energized and attract the handle 26 of the engineer's valve 12 to prevent said valve from being elevated by the air pressure admitted therebeneath through the pipe 18. When the valve 12 is so held by the magnet 25 against upward movement, the plunger 4 will be shifted slightly downwardly, by engagement of the shoe 9 with the cam-rail 10, and immediately returned to its normal upper position by air pressure maintained beneath the piston head 22 through the communicating pipes 21 and 17; the energized magnet 25 thus acting to prevent the brakes being set by the action of the cam-rail 10.

As shown at the left of Fig. 7, the several magnets 23 of the cam-rail 10 are connected in series with a local circuit 27, provided with a switch 28 normally held in closed position by a relay 29 in a track circuit 30 of the next block section 31; said local circuit being provided with a normally open contact 32 adapted to be closed by the weight of a passing train.

It will be understood that when the block section 31 is clear, the switch 28 will be maintained in closed position, and a train approaching the cam-rail 10 of the next block section will close the open contact 32 to complete the local circuit 27; thereby causing the electro-magnets 23 to be energized and producing induced currents in the shoe coil 24 for energizing the electro-magnet 25. The magnet 25 will then hold the engineer's valve 12 against shifting and prevent the brakes being set by the elevation of the shoe 9 by the cam-rail 10; thereby permitting a train to continue on to the clear block section 31. However, should there be a train on said block section 31, the track circuit 30 would be short circuited through the car wheels and axles, and the switch 28 shifted to open position by its spring 33; thereby maintaining the local circuit 27 open, and preventing energization of the rail magnets 23. Under these conditions, the electro-magnet 25 would not be energized, and the brakes would be applied by the action of the cam-rail 10 on the shoe 9, as previously described; thereby preventing the unintentional entrance of a train on to the occupied block section 31.

Fig. 3 illustrates a slight modification, in which an electro-magnet 34 in series with the shoe coil 24 acts upon a lever 35 for shifting the latter beneath the handle 36 of the engineer's valve, for positively locking said valve against upward shifting.

Fig. 8 illustrates a modified construction, in which the electro-magnets 23 of the cam-rail 10 are connected in series in a local circuit 37, provided with a normally open switch 38 and closed switch 39; said switches being formed of magnetic material, such as iron, and maintained in their normal positions by

gravity or springs. An electro-magnet 40 is wound in series with a track circuit 41 of the succeeding block section 42, and placed in such juxtaposition to the initial rail magnet 23 that the shoe 9 will bridge the cores of said two magnets during its initial travel on the cam-rail 10; thereby distributing the magnetic field of the energized magnet 40 to the adjacent magnet 23, and causing the latter to draw the iron switch 38 against a contact 43 to close the local circuit 37 through the rail magnets 23 and the normally closed switch 39. The energized rail magnets 23 will then energize the magnet 25 for holding the engineer's valve 12 against upward shifting to prevent the brakes being set by the action of the cam-rail 10 on the shoe 9, in the previously described manner. As the shoe 9 approaches the end of travel on the cam-rail 10, it bridges the cores of the final electro-magnet 23 and an adjacent magnet 44; thereby distributing the magnetic field of the energized final magnet to said magnet 44, and causing the latter to attract the switch 39 to open the local circuit 37. On the other hand, should there be a train on said block section 42, the track circuit 41 would be short circuited through the carwheels and axles, and the magnet 40 would not be energized for closing the local circuit 37 in the previously described manner. Under these conditions, there would be no currents induced in the shoe coil 24 for energizing the magnet 25, and the brakes would be applied by the action of the cam-rail 10 on said shoe 9. I have shown a relay 45 in the track circuit 41 for actuating an armature 46 to control signals or other devices usually employed in block systems.

Fig. 9 illustrates a construction similar to that of Fig. 8, in which the local circuit 47 is provided with any well known form of current reverser 48 and with an additional switch 49 normally maintained in closed position by a relay 50 in the track circuit 51 of the block section 52; thereby avoiding all chance of residual magnetism in the rail magnets 23 and insuring the opening of the local-circuit switch 49 when the block section 52 is occupied by a train.

The right-hand portion of Fig. 7 illustrates a further modification, in which the track circuit 53 of the block section 54 is in series with a magnet 50 similar to that previously described and with a relay 55 for normally maintaining the local circuit 56 closed through a switch 57; a relay 58 being shown in the track circuit 30 for controlling signals or other devices usually employed in block systems. In this modified construction, the local circuit 56 through the rail magnets 23 will be opened upon short circuiting of the track circuit 53 by the passage of the train on to the block section 54.

Figs. 5 and 6 illustrate a preferred con-

struction, in which a balanced engineer's valve 59 is mounted in a casing 60 for normally maintaining communication between the train-pipe 61 and a pipe 62 leading to 5 any suitable source of air under pressure; said casing being provided with an exhaust opening 63, and with a passage 64 for placing it in communication with a pipe 65 leading to a source of air under pressure. A 10 plunger 66 is mounted in the casing 60 for controlling the passage 64, and is normally maintained in its lower open position, as by a tension spring 67; said plunger being provided with an armature 68 extending within 15 a solenoid 69. The solenoid 69 is shown in a local cab circuit 69^a, which is provided with a normally open switch 69^b controlled by a magnet 69^c in circuit with the coils of the shoe 9. In this construction, currents generated 20 in the shoe 9 during travel along the magnetic rail 70 will energize the magnet 69^c and close the cab circuit 69^a through the solenoid 69; thereby drawing the plunger of the solenoid 69 to its upper position and 25 closing the passage 64, as shown in Fig. 5. It will be obvious that the cab circuit 69^a could be omitted, if desired, and the solenoid connected in circuit with the coils of the shoe 9. The connections to said magnet rail 30 70 are exactly similar to those previously described in reference to the magnetic rail 10, and a further description would be mere repetition. A piston valve 71 is mounted in the casing 60 for controlling the passage 64, 35 and carries a roller 72, which normally rides on the track rail 73 and is of sufficient width to engage a cam-rail 74 positioned adjacent to the magnetic rail 70. In this construction, it will be clear that, if the magnetic 40 rail 70 is not energized during the elevation of the piston valve 71 by the cam-rail 74, the engineer's valve 59 will be forced upward by the air pressure admitted through the passage 64, to close communication between 45 the air-pressure pipe 62 and the train-pipe 61 and to place said train-pipe in communication with the exhaust opening 63; thereby causing the brakes to be set. On the other hand, if the magnetic rail 70 be energized, 50 currents will be generated in the shoe 9, transmitted to the solenoid 69 and raise the plunger 66 for closing the passage 64; thereby preventing the flow of air through the passage 64 for raising the engineer's valve 55 59 when the piston valve 71 is elevated by the cam-rail 74. The air-pressure pipe 65 is shown provided with a branch 75 leading above the piston valve 71 for yieldingly maintaining the latter in engagement with 60 the rails, whereby said valve will be forced downward to open position upon breakage or displacement of its parts from engagement with said rails, thereby giving immediate warning of such derangement by 65 throwing on the brakes. The piston valve 71 is preferably provided with a recess 76 adapted to establish communication between the passage 64 and a bore 77 leading above the plunger 66 in the normal position of said valve 71, whereby the residual pressure of air entrapped within the passage 64 will tend to return said plunger 66 to its lower open position.

Fig. 4 illustrates a modification, in which the piston valve 71 is connected by a link 78 75 to a bell-crank lever 79 and 80 having its fulcrum 81 yieldingly maintained by a spring 82 in the forward end of a slot 83 in a base plate 84 on the locomotive; the arm 79 of said bell-crank lever carrying a 80 shoe 85 for engaging a magnetic cam-rail 86 provided with electrical circuits similar to those described in reference to the preceding figures. The link 78 is secured to a pivot 87 on the lever arm 80 which engages an 85 angularly-extending guide slot 88 in the plate 84; the lower portion of said slot extending substantially concentrically to the normal forward position of the lever fulcrum 81. In this construction, if the magnetic cam-rail 86 is not energized during the elevation of the shoe 85 thereby, such elevation will act to swing the bell-crank lever about the normal forward position of its fulcrum 81 and depress the piston valve 71 90 to open the passage 64 for the passage of air therethrough. On the other hand, if the magnetic rail 86 is energized, it will tend to cause the shoe 85 to strongly adhere thereto, thereby causing said shoe to drag 100 the lever fulcrum 81 rearwardly in its slot 88 against the tension of the spring 82. In this operation, the pivot 87 will be shifted rearwardly in its angularly-extending guide slot 88 and the lever fulcrum 81 will be elevated in the raised rear portion of the slot 83; the link 78 permitting such movement of the parts without shifting the piston valve 71.

If desired, the shoe 85 could be provided 105 with coils for inducing currents in the solenoid 69, in the previously described manner, but such solenoid and its actuated plunger are not necessary in this modified construction.

I have illustrated and described preferred 110 and satisfactory constructions, but changes could be made within the spirit and scope of my invention.

I claim:—

1. In an automatic train controller, the 115 combination of an air-brake valve, fluid-pressure means for shifting said valve, controlling means for said fluid-pressure means, means for actuating said controlling means, an electro-magnetic device for controlling 120 the shifting of said air-brake valve, means for energizing said electro-magnetic device, and manually-operated means for shifting 125 said air-brake valve independently of said fluid-pressure means.

2. In an automatic train controller for use with block systems of railways, the combination of an air-brake valve, fluid-pressure means for shifting said valve, controlling means for said fluid-pressure means, means adjacent the end of a block section for actuating said controlling means, an electro-magnetic device for controlling the shifting of said air-brake valve, electro-magnetic means for producing a magnetic field for energizing said electro-magnetic device during such actuation of said controlling means, and means in electrical circuit with the track rails of the succeeding block section 15 for controlling said electro-magnetic means.
3. In an automatic train controller for use with block systems of railways, the combination of an air-brake valve, fluid-pressure means for shifting said valve, controlling means for said fluid-pressure means, means adjacent the end of a block section for actuating said controlling means, an electro-magnetic device for controlling the shifting of said air-brake valve, electro-magnetic means for energizing said electro-magnetic device during such actuation of said controlling means, a local electrical circuit for said electro-magnetic means, and means in electrical circuit with the track rails of the succeeding block section 20 for controlling said local circuit.
4. In an automatic train controller for use with block systems of railways, the combination of an air-brake valve, fluid-pressure means for shifting said valve, controlling means for said fluid-pressure means, means 25 adjacent the end of a block section for actuating said controlling means, an electro-magnetic device for controlling the shifting of said air-brake valve, electro-magnetic means for energizing said electro-magnetic device during such actuation of said controlling means, a local electrical circuit for said electro-magnetic means, and means in electrical circuit with the track rails of the succeeding block section 30 for controlling said local circuit.
5. In an automatic train controller for use with block systems of railways, the combination of an air-brake valve, fluid-pressure means for shifting said valve, controlling means for said fluid-pressure means, means 35 adjacent the end of a block section for actuating said controlling means, an electro-magnetic device for controlling the shifting of said air-brake valve, electro-magnetic means for energizing said electro-magnetic device during such actuation of said controlling means, a local electrical circuit for said electro-magnetic means, and means in electrical circuit with the track rails of the succeeding block section 40 for normally maintaining said local circuit closed.

5. In an automatic train controller for use with block systems of railways, the combination of an air-brake valve, fluid-pressure means for shifting said valve, controlling means for said fluid-pressure means, means adjacent the end of a block section for actuating said controlling means, an electro-magnetic device for controlling the shifting of said air-brake valve, electro-magnetic means for energizing said electro-magnetic device during such actuation of said controlling means, a local electrical circuit for said electro-magnetic means, and means in electrical circuit with the track rails of the succeeding block section 45 for normally maintaining said local circuit closed.

5. In an automatic train controller for use with block systems of railways, the combination of an air-brake valve, fluid-pressure means for shifting said valve, controlling means for said fluid-pressure means, means adjacent the end of a block section for actuating said controlling means, an electro-magnetic device for controlling the shifting of said air-brake valve, electro-magnetic means for energizing said electro-magnetic device during such actuation of said controlling means, a local electrical circuit for said electro-magnetic means, a switch in said 50 local circuit, resilient means for shifting said switch to open position, and an auxiliary electro-magnet in circuit with the track rails of the succeeding block section for maintaining said switch in closed position. 55

In testimony whereof, I affix my signature, in presence of two witnesses.
